UNITED STATES PATENT OFFICE.

HENRY DONOVAN, OF NEW BEDFORD, MASSACHUSETTS.

CRIMPING-MACHINE.

SPECIFICATION forming part of Letters Patent No. 388,845, dated September 4, 1888.

Application filed June 22, 1888. Serial No. 277,892. (No model.)

To all whom it may concern:

Be it known that I, HENRY DONOVAN, of New Bedford, in the county of Bristol, State of Massachusetts, have invented a certain new and useful Improvement in Leather-Crimping Machines, of which the following is a description sufficiently full, clear, and exact to enable any person skilled in the art or science to which said invention appertains to make and use the same, reference being had to the accompanying drawings, forming part of this specification, in which—

Figure 1 is an aside elevation, partly in section, of my improved leather-crimping machine; Fig. 2, a front elevation of the same, certain parts being shown in section on line xx in Fig. 1; Figs. 3, 4, 5, 6, views showing certain details of construction; and Fig. 7 an isometrical perspective view of the body and jaws detached.

Like letters and figures of reference indicate corresponding parts in the different figures of the drawings.

My invention relates to that class of leather-crimping machines which are provided with adjustable crimping-jaws and a series of crimping plates or forms adapted to pass successively through said jaws; and it consists in certain novel features, as hereinafter fully set forth and claimed, the object being to produce a cheaper, simpler, and more effective device of this character than is now in ordinary use.

The nature and operation of the improvement will be readily understood by all conversant with such matters from the following explanation:

In the drawings, Λ represents the table, Z the frame-work of the machine, N the body of the crimper, and R Q the crimping-jaws.

The frame-work consists, primarily, of two centrally-arranged vertical standards, B , connected at the top by a brace, C .

Two vertical standards, B^2 , are secured to the table Λ in the same vertical plane, respectively, as the standards B , and are connected therewith centrally by cross bars, 60 , and at the top by a curved arm, W .

A vertically-arranged guide-plate, v , is secured centrally between the front and rear standards, B^2 B , and provided with a curved upper edge, 61 , the purpose of said plate being hereinafter described.

A vertically-arranged locking plate, z , is centrally disposed in the same vertical plane as the guide-plate v , and is provided in its upper portion with a curved edge, 75 , and a series of holes, y , (see Fig. 1.) for a purpose hereinafter described.

A horizontally-arranged shaft, L , (see Fig 2,) is journaled in the central standards, B B^2 , and provided on its rear end with a large gear, J .

A bracket, D , projects rearward from the central standard B , a horizontally-arranged shaft, K , being journaled in said bracket and standard and provided with driving pulleys E F G and the pinion H , which intermeshes with the gear J .

The body N consists, essentially, of an oval plate, to the rear side of which, near one of its ends, is secured a sleeve, 62 , which is mounted on the shaft L , a sprocket-wheel, 10 , being secured to said shaft on the face of said body.

A stub-shaft, 22 , projects from the opposite end of the body N , and mounted on said shaft there is a sprocket-wheel, 15 , an endless chain 75 belt, 20 , being disposed on said sprockets and adapted to travel as the shaft L rotates. An oval track, O , is secured to the face of the body N and follows the course of said chain. Carriers r (see Figs. 3 and 4) are secured at $8c$ intervals to the belt 20 , said carriers being provided on their under sides with grooves 63 , (see Fig. 4,) having curved edges 64 , to adapt them to travel on the track O as the chain 20 moves.

The crimping-plates P , of the shape usual in machines of this description, consist of a metallic plate, 13 , provided with a leather covering, 14 .

Each carrier r is provided with a dovetail 90 groove in its outer edge, a plate, 12 , having a dovetail, 65 , adapted to enter said groove, being secured by screws t to one edge of each of the crimping-plates P , thus enabling said plates to be readily and detachably secured to 95 said carriers.

The crimping-jaws consist of a fixed jaw, Q , preferably formed integral with the body N and projecting laterally from one side thereof, and a movable jaw, R , hinged at 66 (see Fig. 1) to a frame, T , hereinafter described.

The upper portion or mouth of the jaws is of the usual form, being triangular in side elevation, and have their inner faces corrugated.

gated, as shown at 67 in Fig. 6, the corrugations following the curve of the mouth of said jaws and increasing in distance apart as the bottom is approached.

- 5 The frame T consists of two parallel side bars, 68, (see Fig. 1,) and two crossed side bars, 70, (see Fig. 5,) one end of said crossed bars being connected with the parallel bars 68 by end bars, 69, which are fitted to slide horizontally in holes formed in the center of the body N, the opposite ends of said side bars being connected by similar end bars, 71, which are fitted to slide in holes in the outer edge of the fixed jaw Q, openings 72 being provided 15 in the edge of the movable jaw R to allow said end bars to pass.

The movable jaw R is hinged at 66 to the bars 68, as described, and a block, 73, being secured between said bars, near the outer edge 20 of said jaw, and provided with a thumb-screw, q, which passes into said jaw, and by means of which the distance between the jaws can be regulated.

A bar, S, is secured to the body N and fixed 25 jaw Q between the parallel bars 68 by means of braces 76, the outer end, 77, of said bar S being provided with a pin-hole, x, (see Fig. 1,) adapted to register with the holes y in the locking-plate z.

- 30 By inserting a pin in the holes x y the body N may be secured in any desired position on the plate z.

A semicircular plate, M, is secured centrally to the sleeve 62, near the standard B, said 35 plate being provided on its periphery with a track or groove, p, in which the arms of a forked traveler, 78, are fitted to slide, said traveler being provided with a pulley, k, as shown in Fig. 2.

- 40 A horizontally - arranged rearwardly - projecting slotted stud, j, is secured centrally at the intersection of the crossed side bars 70, a cord, m, being fastened to said stud and passing over the pulley k, a weight, a, being secured to the outer end of said cord. A wedge-shaped block, i, is secured to the crossed-bars 45 70 within the stud j. A rod, f, is pivoted horizontally in the body N, so that its forward end projects into the path of the carriages r above the jaws Q R, as shown in Fig. 1.

To the rear end of the rod f is pivoted a vertically-arranged bar, g, which passes through the stud j, and is provided with a wedge-shaped block, h, adapted to engage the wedge-block i 55 described. A toggle-jointed rod, b, is pivoted in the body N, so that its forward end may be made to project into the path of the carriages r below the jaws Q R, (see Fig. 1,) the rear end of said rod b being pivoted to the vertical rod g, which is extended downward, so that an ordinary treadle may be attached thereto for operating the mechanism by foot-power, if desired.

In the use of my improvement the bar S is 65 secured to the plate z in the position desired by means of a pin passing through a hole, x,

therein and through a hole, y, in said plate. Power being applied to one of the pulleys E F G, the shaft L is rotated, causing the belt 20 to travel from left to right and carry with it the 70

carriages r, secured thereto, and with them the crimping plates P, which successively pass between the jaws R Q. The leather to be crimped is laid upon the jaws in the usual manner, and as the plates pass said jaws is bent or molded 75

in the form desired. As a plate P approaches the jaws, its carriage r strikes the forward end of the rod f, causing the vertical rod g to be raised, thereby removing the wedge-block h from the stud j. As soon as this occurs the 80 weight a, attached to said stud as described, draws backward the sliding frame-work T and forces the movable jaw R, attached thereto, against the leather to be crimped on the plate or former P as it passes between the jaws. 85 The corrugations 67 on the inner faces of the jaws enable them to take a firmer hold upon the leather and crimp the same much more perfectly than when smooth jaws are used.

By means of the thumb-screw q the movable 90 jaw R may be so adjusted in relation to the jaw Q that the different thicknesses in the same piece of leather may be readily compensated for. After the plate P has passed through the jaws its carriage r strikes the forward end of the toggle-jointed rod b, which had been thrown into its path by the rod g as it was drawn up. This pulls the rod g downward again and forces the wedge-block h into contact with the block i, thereby moving the 100 frame T forward, and with it the movable jaw R, thus opening the jaws to receive the next plate P.

In crimping-machines as ordinarily constructed it is necessary to await the return of 105 the crimping-plate after its passage through the jaws before another piece of work can be placed in position to be crimped. In my improved crimpler the plates follow each other successively, one entering the jaws directly 110 after the preceding one leaves it, thus enabling the work to be greatly facilitated. By covering the steel plates P completely with a leather covering, 14, as described, so that said leather intervenes between the form and upper to be 115 crimped, it is not necessary to remove and replace it with each upper crimped, as is necessary in machines of ordinary construction. Moreover, the cover being fastened to the form renders it possible to remove the upper 120 without losing the crimp, as the cover being soft and pliable easily bends when removed. The upper, after being crimped, can readily be removed from the form or plate P while in motion, which avoids the necessity of stopping the form to remove the work, as is customary in machines of this class. By reversing the position of the body N and securing it in position by means of a pin passing through the hole x in the locking-bar S and into a hole, 125 w, in the curved brace W the plates P may be made to pass upward through the jaws R

Q. This is of particular advantage when the upper is reversed or turned right side out to be crimped the second time, as it is much more easily placed upon the form for this purpose than upon the jaws in the ordinary manner, it being understood that uppers are usually crimped the first time with the unfinished side of the leather outward, because the jaws engage the rough surface more readily and remove the wrinkles more effectually.

My improvement also saves time in the manipulation of the upper, as by placing the hand flatly against one side of the plate P and grasping the flap of the upper on the other side it may be readily turned while removing it from the plate.

I am aware that leather-covered jaws and plates and corrugated jaws have been used in this class of machines, and I do not herein claim the same broadly when in and of themselves considered.

Having thus explained my invention, what I claim is—

1. In a crimping-machine, the combination of a body provided with a track, sprocket-wheels journaled on said body, an endless chain belt disposed on said sprocket-wheels, carriers fitted to travel on said track and carrying crimping-plates, said carriers being connected with said belt, a pair of jaws, one of which is secured to said body and the other hinged to a movable frame passing through said body and fixed jaw, means for moving said frame laterally and closing and opening the jaws, and actuating mechanism for said chain, substantially as set forth.

2. In a crimping-machine, the combination of an adjustable oval-shaped body provided with a track, an endless chain disposed on sprocket-wheels carried by shafts journaled in said body, a series of carriers disposed on said track and actuated by said chain, crimping-plates detachably secured to said carriers, a fixed jaw on said body, and a movable jaw hinged to a frame-work fitted to slide laterally through said body and fixed jaw by which the distance between said jaws may be regulated, substantially as described.

3. In a crimping-machine, the combination of an oval-shaped adjustable body journaled on a shaft and provided with a track, an endless chain belt disposed on a sprocket on said shaft and a sprocket on a stub-shaft projecting from said body, carriers attached to said chain and adapted to slide on said track, a crimping-plate provided with a flexible covering and detachably secured to each of said carriers, a fixed jaw secured to said body and provided with a corrugated crimping surface, a locking-bar secured to said body and jaw for holding the same in position, a frame fitted to slide laterally through said body and jaw, a movable jaw hinged in said frame and having a corrugated crimping-surface, and mechanism adapted to be released or let off by said carriers, whereby said frame may be

moved and the distance between said jaws regulated, substantially as set forth.

4. In a crimping-machine, the combination of a body journaled on a driving-shaft and provided with a track and a fixed crimping-jaw, carriers bearing crimping-plates disposed on said track and actuated by an endless chain belt driven by said shaft, a laterally-adjustable frame fitted to slide in said body and jaw, a movable jaw hinged in said frame, a horizontally-arranged rod pivoted in said body and projecting into the path of said carriers, and a vertically-arranged bar pivoted to said rod and provided with a wedge-block so adapted to engage a block disposed in a slotted stud on the rear of said frame, and a weight secured to said stud, whereby when said carriers engage said rod and disengage said block said weight will force the movable jaw against the crimping plate as it passes between the jaws, substantially as described.

5. In a crimping-machine, the combination of a body having a fixed jaw, a frame fitted to slide laterally in said body and jaw, a movable jaw hinged to said frame, a slotted stud secured to said frame and provided with a wedge-block, a cord and weight secured to said stud, a rod pivoted in said body above said jaws, a toggle-jointed rod pivoted in said body below said jaws, and a vertical bar hinged to the rear end of said rods and provided with a wedge adapted to engage the wedge in said stud, substantially as set forth.

6. In a crimping-machine, the combination of a frame-work provided with holes for receiving a locking-pin, an oval body journaled on a driving-shaft in said frame-work and provided with a track and a fixed crimping-jaw, a sleeve on said shaft and secured to said body, a chain belt disposed on a sprocket-wheel on said shaft and on a sprocket on a stub-shaft projecting from said body, carriers fitted to slide on said track and secured to said chain, crimping-plates having flexible coverings and adapted to be detachably secured to said carriers, a frame fitted to slide laterally in said body and jaw, a locking-bar secured to said body and jaw and provided with a pin-hole adapted to register with the holes in said frame-work, a movable jaw hinged to said sliding frame, a screw for adjusting said jaw, and mechanism adapted to be let off or operated by the crimping-plates, whereby said movable jaw may be forced against the leather on said plates as they pass, substantially as described.

7. In a crimping-machine, the carrier r, provided with the slot 63, having the curved side 64 and a dovetail groove on its outer edge, in combination with the crimping-plate P, provided with the dovetail block 12 and flexible covering 14, substantially as set forth.

8. In a crimping-machine, the oval body N, journaled on the shaft L, and provided with the track O and chain belt 20, in combination with the carrier r, secured to said chain and

fitted to slide on said track, and the crimping-plate P, secured to said carrier, substantially as described.

9. In a crimping-machine, the semicircular plate M, provided with the groove p and journaled on the shaft L, in combination with the forked traveler 78, provided with the pulley k for the cord m, carrying the weight a, whereby the jaws of the crimper are automatically adjusted, substantially as set forth.

10. In a crimping-machine, the sliding

frame T, having the slotted stud j and wedge-block i, in combination with the movable jaw R, hinged to said frame, and mechanism adapted to be let off or operated by the crimping-plates, whereby said movable jaw is forced against the leather on said plates, substantially as described. 15
